UNITED STATES PATENT OFFICE.

LEONID DOUZHAEV, OF NEW YORK, N. Y.

WATER-FEED APPARATUS FOR STEAM-BOILERS OR THE LIKE.

1,302,390.

Specification of Letters Patent. Patented Apr. 23, 1919.

Application filed June 19, 1916. Serial No. 249,554.

To all whom it may concern:

Be it known that I, LEONID DOUZHAEV, a citizen of the Russian Republic, and residing at New York, borough of Manhattan, 5 and State of New York, have invented certain new and useful Improvements in Water-Feed Apparatus for Steam-Boilers or the like, of which the following is a full and clear specification, illustrated in the 10 accompanying drawings, the particular novel features of my invention being more fully pointed out in the annexed claims.

For pumping water into a steam boiler in action it is necessary to apply positive 15 work against the pressure existing in the boiler. Usually steam from the same boiler is applied for this work whereby the steam runs freely from the boiler to a steam pump, injector, or other similar apparatus 20 where the steam works through expansion.

Feeding means of this character heretofore used in the art show an efficiency which is low compared with the work required and, thus the losses incurred thereby constitute 25 an appreciable item in the cost of operation of the steam plant.

The feeding apparatus according to my invention raises the efficiency in the performance of this work to such a degree that 30 substantially only the comparatively small friction losses in the apparatus itself constitute the wasted energy.

In the accompanying drawings:

Figure 1 is a longitudinal vertical section through the apparatus on the line E—F in Fig. 5;

Fig. 2 is a transverse vertical section on the line A—B in Fig. 1;

Fig. 3 is a transverse vertical section on the line C—D in Fig. 1;

Fig. 4 is a detail end view in larger scale of one of the slides for controlling the passage of the steam; and

Fig. 5 is a full end view of the entire 45 apparatus, showing how it is mounted on the boiler.

The construction of the apparatus is as follows:

Referring to Figs. 1 and 5, 10 represents 50 a substantially rectangular casing which is provided with a cylindrical horizontal portion 11 in which a piston 12 is slidingly disposed. Piston 12 has a central, transverse wall 13 dividing it into two compartments 14 and 15 of equal volume. Each compartment is provided with a series of

ports 16 arranged in a peripheral row and suitably spaced apart, each row being equidistant from the central wall 13. Midway between its ends, cylinder 11 widens for a short distance into a transverse compartment 17 substantially of the form shown in Fig. 2, which terminates at its lower portion in the water discharge pipe 18 as shown in Figs. 1 and 3. The throw of piston 12 65 is chosen so that when it reciprocates, its two peripheral rows of ports 16 will alternately place compartments 14 and 15 into communication with compartment 17 and thus with discharge pipe 18. The wall portion of cylinder 11, located within the upper portion of casing 10 is provided with ports 19 and 20, which are spaced from the center of the cylinder such a distance that when the port row 16 of one piston compartment registers with compartment 17, the port row of the piston compartment 14 will register with port 19. When the piston is shifted into the other extreme position in which the ports of compartment 14 register 75 with compartment 17, ports 16 of compartment 15 register with ports 20.

Cylinder 11 is moreover provided with two transverse compartments 21 and 22 as may be seen from Fig. 2 in which compartment 21 is shown. These compartments extend at the under portion of cylinder 11 well toward its ends, as may be seen from Fig. 1 (see 21^a, 22^a), where they form steam chests, the purpose of which will be explained presently. Between each steam chest 21^a and 22^a and the lower portion of the cylinder wall is mounted in the main casing 10 a slide 23, 24 respectively. I prefer the cylindrical form for these slides, 80 the end view of slide 23 being shown in Fig. 4 in larger scale. As will be seen from Fig. 1, slides 23 and 24 are hollow and provided at the portion adjacent to the cylinder wall with a longitudinal slot 25, 26 respectively, which registers with a slot of similar width and suitable length 26 and 27, respectively, provided in the cylinder wall, such that fingers 28, 29, fastened to the ends of piston 12, may extend respectively through slots 26 and 27 for the purpose of shifting the slides longitudinally a certain distance when the piston 12 reciprocates. Slides 23 and 24 are open at their outer ends and closed at their inner ends 95 by a screw plug 30, 31 respectively, each of which is provided with a T boring 32, 33

respectively, so that by screwing these plugs more or less into their slide, the admission of steam into the interior of these slides can be throttled at will. The compartment 5 in which each slide operates is connected respectively with chests 21^a and 22^a by means of a port 34, 35, these ports being alternately closed and opened by their respective slides when the piston 12 operates these 10 slides through fingers 28 and 29, as described before. The cylinders for the slides are connected at their outer ends to the open air by means of ports 36, 37 respectively which likewise are alternately opened and 15 closed by their respective slides when the piston 12 oscillates. These slides can be removed from their respective cylinders when 20 plugs 38, 39 are unscrewed. Each end of piston 12 is provided with a central boss 21 which abuts against a rod 42 provided 25 in the end covers 43 of cylinder 11 when piston 12 arrives at these respective ends. Each rod 42 carries a washer 43 which is slipped over the reduced outer ends of rods 25. Moreover, each cylinder cover has threaded to a central boss through which rod 42 passes, a gland 44 in the interior of which a bolster 45 is disposed which abuts 30 with one side against the bottom of the gland and with the other side against washer 43. Normally, as shown at the right hand end of the cylinder, bolster 45 is expanded. As soon as the piston arrives at one end of the cylinder (see left hand end of Fig. 1), 35 boss 41 abuts against rod 42 which compresses bolster 45 and thus relieves the sheek of the impact of the piston against the end covers of the cylinder. The reduced ends of rods 42 protrude through the outer 40 covers of the cylinder and are shown broken off in Fig. 1. They may be provided with any suitable means not shown here, for pushing rods 42 slightly inward so as to start the piston 12 on its stroke in case it 45 should have stopped at a point where it will not start automatically to operate in the manner which will be described presently.

The upper portion of casing 10 is provided with a water inlet 46, which discharges 50 the water into the heat insulating pad 60, and chest 17, as shown in Fig. 3, is provided with a steam supply pipe 47 which leads to the boiler 48 (Fig. 5). The location of the entrance of this steam supply 55 pipe can not be seen in Fig. 1, but is merely indicated by a dotted circle.

Steam chests 21^a and 22^a are in communication with each other by passages 48 leading around either side of chest 17 (see Figs. 60 1, 2 and 3). These chests 21^a and 22^a can be supplied with live steam from the boiler by means of supply pipe 49 which enters 65 at one of the passages 48 (see Figs. 2 and 3). The entrance of this supply pipe can not be seen in Fig. 1, but is indicated by a

dotted circle 49. Supply pipe 49 passes into a dome 50 provided at the point where pipe 47 enters the boiler 48 and in this dome a valve 51 of any suitable kind may be arranged, which can be temporarily opened by 70 a chain 52 or any other suitable means. As will be seen from Fig. 5, the steam from the boiler enters the dome directly and from there may pass into pipe 49 when valve 51 is open, whereas pipe 47 passes through 75 dome 50 and terminates in the boiler slightly below the normal water level as shown. The water discharge pipe 18 passes into the boiler and terminates a considerable distance below the normal water level as shown 80 in Fig. 5. This pipe may be closed by means of hand valve 53.

The operation of the device is as follows: Let us assume the water has fallen in the 85 boiler a sufficient distance below normal to require feeding of the boiler. Then the lower end of steam pipe 47 is exposed to the live steam. Let us further assume piston 12 stands in the position shown in Fig. 1. Then the steam space of the boiler is in direct communication with chest 17, (Fig. 3). Let us further assume that the upper chest 54 of casing 10 is filled and remains filled with water from fresh water supply pipe 46. In the position in which piston 12 is shown in 90 Fig. 1, there is a free communication between water chest 54 and compartment 14 of piston 12 through ports 16 and 19, so that compartment 14 will fill with water. Slide 23, controlled by the left hand end of 95 piston 12, has been pushed to its farthest left hand position in which it is shown, and also slide 24 has been pushed by the piston to the farthest left hand position. In these positions, slide 23 has established a communication 100 between steam chest 21^a and the space behind the left hand end of piston 12 through port 34 (then uncovered by the slide). The boring of plug 30, interior of slide 23, and slots 25, 26. The exhaust port 36 at 105 that time is covered by slide 23. In this position the space behind the right hand end of piston 12 is in communication with the open air through slots 27, 26, interior of slide 24 and port 37 which is then uncovered by that slide. Port 35 in communication with chest 22^a is then closed by slide 24.

With no steam admitted into chests 21, 22^a, the piston remains stationary and conditions remain in all respects as just described. 110 Now, if the engineer opens for a moment the valve 51 of steam pipe 29, live steam is admitted to chests 21^a and 22^a and thus live steam will reach the space behind the left hand end of piston 12 and, in expanding, 115 push the piston gradually to the right. When the piston has reached its extreme right hand position, ports 16 of compartment 14 register with chest 17 and the water contained in compartment 14 pours out 120

through discharge pipe 18 into the boiler. It was pointed out before, when describing the position of piston 12 shown in Fig. 1, that then steam of boiler pressure is contained in compartment 15. This quantity of steam under boiler pressure is now conveyed in this compartment to the right, when piston 12 shifts, as has just been described, and on its way to the right, piston 12 discharges from its compartment 15 this steam, through its ports 16 into chests 22 and 22^a, so that when piston 12 arrives at the right hand end and moves slide 24 to the right, communication is established between chest 22^a, through port 35, plug 31 and slots 26, 27, and the space behind the right hand end of the piston, so that the piston will now be pushed back to the left. In the meantime, when piston 12 stands in the right hand position, ports 16 of compartment 15 register with ports 20 and thus fill with water, while compartment 14 discharges its water into the boiler. Now all the functions occur when the piston moves to the left, which have been described with respect to the movement of the piston 12 to the right, i. e., the expanded steam which has pushed piston 12 to the right is discharged when port 36 is uncovered by slide 23 and it remains uncovered while piston 12 moves back to the left; compartment 14 fills with live steam from chest 17 and discharges this steam through chest 21 into chest 21^a, whence it can pass behind the left hand end of the piston, since slide 23 is again pushed into the position shown in Fig. 1. Thus, the piston continually automatically oscillates back and forth, alternately filling and discharging compartments 14 and 15 into the boiler through discharge pipe 18. This operation continues until the water in the boiler arrives at the normal level, when the mouth of steam pipe 47 is sealed by the water and steam supply into chest 17 is interrupted. Now, the operation of the piston stops and thus the water supply into the boiler ceases. Should the piston stop at such point where on opening valve 51 for a moment, steam cannot reach either end of cylinder 11, then one or the other rod 42 is pushed in by hand by means of its outwardly protruding end, and the piston brought into either end position where steam can be supplied and the pump started in the manner described before.

By means of screws 40 provided in the outer ends of slides 23 and 24, the throw of these slides may be adjusted to a nicely and the pump be properly timed; also, as pointed out before, by properly adjusting the position of plugs 30 and 31 in these slides, the steam passing through these slides may be throttled to the proper degree so as to adjust the speed of the pump.

I claim:

3. In a water feeding device for steam

boilers or the like, the combination of a hollow reciprocating member, having two separate compartments suitably disposed to alternately receive feed water and discharge it into the boiler by such reciprocation, means for supplying steam from the boiler alternately to each of said compartments as it discharges its water contents, and means controlled by the reciprocation of said member for directing the steam supplied to said compartments alternately behind the ends of said member to cause its reciprocation.

2. In a water feeding device for steam boilers or the like, the combination of a hollow reciprocating member, having two separate compartments suitably disposed to alternately receive feed water and discharge it through a common discharge pipe into the boiler by such reciprocation, means for supplying steam from the boiler alternately to each of said compartments as it discharges its water contents, and means controlled by the reciprocation of said member for directing the steam supplied to said compartments alternately behind the ends of said member to cause its reciprocation.

3. In a water feeding device for steam boilers or the like, the combination of a cylinder closed at its ends and having a feed water chest, a hollow reciprocating piston contained in said cylinder and being transversely divided into two separate compartments, said cylinder and piston walls having ports suitably disposed to permit said compartments to alternately receive feed water from said chest and discharge it into the boiler by the piston reciprocation, means for supplying steam from the boiler alternately to each of said compartments as it discharges its water contents, and means controlled by the reciprocation of said piston for directing the steam supplied to a compartment behind that end of the piston where such compartment is located when that piston end has reached the cylinder end, to move the piston toward the other end of the cylinder.

4. In a water feeding device for steam boilers or the like, the combination of a cylinder closed at its ends and having a feed water chest, a hollow reciprocating piston contained in said cylinder and being transversely divided into two separate compartments, said cylinder and piston walls having ports suitably disposed to permit said compartments to alternately receive feed water from said chest and discharge it into the boiler by the piston reciprocation, means for supplying steam from the boiler alternately to each of said compartments as it discharges its water contents, a steam chest adjacent to each cylinder end adapted to receive steam from the piston compartment as the piston travels toward that end, a slide for each steam chest, controlled by the

movement of the piston, for admitting the steam from the chest to the cylinder end at which the piston has arrived, the slide at the other cylinder end adapted to simultaneously connect that end to the outside.

5. In a water feeding device for steam boilers or the like, the combination of a cylinder closed at its ends and having a feed water chest, a hollow reciprocating piston contained in said cylinder and being transversely divided into two separate compartments, said cylinder and piston walls having ports suitably disposed to permit said compartments to alternately receive feed water 10 from said chest and discharge it into the boiler by the piston reciprocation, means for supplying steam from the boiler alternately to each of said compartments as it discharges its water contents, a steam chest adjacent to each cylinder end adapted to receive the steam from the piston compartment as the piston travels toward that end, a slide for each steam chest, controlled by the movement of the piston, for admitting 15 the steam from the chest to the cylinder end at which the piston has arrived, the slide at the other cylinder end adapted to simultaneously connect that end to the outside, and adjustable means on each slide for controlling the amount of steam passing through it, to control the reciprocating speed of the piston.

6. In a water feeding device for steam boilers or the like, the combination of a cylinder closed at its ends and having a feed water chest, a hollow reciprocating piston contained in said cylinder and being transversely divided into two separate compartments, said cylinder and piston walls having 20 ports suitably disposed to permit said compartments to alternately receive feed water from said chest and discharge it into the boiler by the piston reciprocation, means for supplying steam from the boiler alternately to each of said compartments as it discharges its water contents, a steam chest adjacent to each cylinder end adapted to receive the steam from the piston compartment

25 movement as the piston travels toward that end, a slide for each steam chest, controlled by the movement of the piston, for admitting the steam from the chest to the cylinder end at which the piston has arrived, the slide at the other cylinder end adapted to simultaneously connect that end to the outside, 55 and a valve controlled steam supply connection from the boiler, common to both steam chests, but independent of the first-named steam supply means, for temporarily admitting steam to either end of the cylinder to 60 normally start the reciprocation of the piston.

7. In a water feeding device for steam boilers or the like, the combination of a cylinder closed at its ends and having a feed 65 water chest, a hollow reciprocating piston contained in said cylinder and being transversely divided into two separate compartments, said cylinder and piston walls having ports suitably disposed to permit said 70 compartments to alternately receive feed water from said chest and discharge it into the boiler by the piston reciprocation, means for supplying steam from the boiler alternately to each of said compartments as it 75 discharges its water contents, a steam chest adjacent to each cylinder end adapted to receive the steam from the piston compartment as the piston travels toward that end, a slide for each steam chest, controlled by 80 the movement of the piston, for admitting the steam from the chest to the cylinder end at which the piston has arrived, the slide at the other cylinder end adapted to simultaneously connect that end to the outside, and 85 adjustable means on each slide for controlling the amount of steam passing through it, to control the reciprocating speed of the piston, and a cushioned push rod at each cylinder end, serving as an abutment for the piston, each rod extending through the cylinder end to permit starting the movement of the piston from the outside in case said slides stand at a point where they prevent steam admission to the cylinder from said chests. 90 95

LEONID DOUNAEV.
